FIG. 2D(iii)

FIG. 2D(ii)

FIG. 2C

FIG. 3

FIG. 5

1

FOOTWEAR TRACTION DEVICE AND
METHOD OF USING THE SAME

FIELD OF INVENTION

The present disclosure generally concerns footwear or footwear accessory devices, systems, and methods for improving traction.

BACKGROUND

Many attempts have been made to create devices that can be worn over footwear to help provide traction on slick or slippery surfaces, in snow, or on ice. Such footwear traction devices are bulky underneath the foot, provide limited traction, are uncomfortable during use, do not stay in place on the footwear, are heavy; and/or provide insufficient durability. In addition, such footwear traction devices work well on only a single specific surface type, such as either pavement or trail.

SUMMARY OF THE INVENTION

One aspect of the present disclosure is directed toward a device that can be worn over footwear to provide traction on a variety of different terrain, from roads and sidewalks to trails, whether snowy, icy, steep, or uneven. Described embodiments comprise polymeric traction bodies that are stepped, sloping lugs having hard tipped spikes which make the described embodiments useful on diverse terrain, e.g., sidewalks as well as trails, whether or not such terrain is steep and/or uneven and whether or not snowy and/or icy. The polymeric traction bodies combined with the openwork base thereunder have a depth (also referred to as “effective height”) suitable for trails and uneven terrain and a material hardness level that makes them suitable and comfortable on smoother surfaces, such as paved surfaces. Moreover, the material hardness level makes for a more comfortable user experience overall.

Described embodiments include a footwear traction device configured to be disposed about footwear comprising an openwork traction base defining a first opening and a second opening, the first opening defined by a first polygonal form having at least four sides with each side having 1 to 4 traction bodies coupled thereto and relatively positioned such that the first opening is predominantly below the forefoot during use; the second opening defined by a second polygonal form having at least three sides and relatively positioned such that the second opening is predominantly below the midfoot and/or hindfoot during use, the openwork traction base comprises at least three traction bodies relatively positioned such that the at least one of the at least three traction bodies are disposed predominantly below the hindfoot during use.

DRAWINGS

FIGS. 1A to 1C are images of a footwear traction embodiment bound around a footwear in the manner intended for use.

FIG. 2A to 2C illustrates an openwork traction base embodiment shown in FIG. 1. 2A illustrates a perspective view of the side of the base that would contact the underside of the footwear. 2B illustrates a perspective view of the side of the base that would engage with the terrain. 2C is a close up perspective view of a traction body shown in 2A.

2

FIG. 2D(i) to 2D(iii) are schematic illustrations of alternative configuration of the openwork traction base.

FIG. 3 depicts a human foot to illustrate the forefoot, midfoot, and hindfoot of a user and correspondingly, the forefoot, midfoot, and hindfoot of footwear or footwear traction device.

FIG. 4 is a perspective view of an elastic band.

FIG. 5 is a perspective view of two traction bodies with a spike having a distal end that is concave or sunken.

10

DETAILED DESCRIPTION

FIG. 1 depicts an embodiment of a footwear traction device 100 in accordance with the present invention. As depicted, the device 100 is configured to be worn over footwear. In FIG. 1, the device 100 is depicted on an item of footwear 200 in the manner intended for use. As shown, a footwear binding member 102 is disposed about a footwear upper 202 and an openwork traction base 101 is disposed on the underside 204 of the footwear 200.

FIGS. 2A and 2B depict an embodiment of an openwork traction base 101. As can be readily appreciated by comparing the figures, the base 101 in FIGS. 2A and 2B illustrate an openwork traction base 101 not coupled to the elastomeric binding member 102 and is in a substantially planar orientation. FIG. 2A depicts the side that is intended to contact the underside of the footwear. FIG. 2B depicts the side that faces opposite the side depicted in FIG. 2A and that is intended to contact the ground when the user is, e.g., walking, running, or hiking.

In accordance with the present invention, the openwork traction base 101 defines a first opening 110 and a second opening 120. The first opening 110 is defined by a first polygonal form 111 that has at least four sides 112. The second opening 120 is defined by a second polygonal form 121 that has at least three sides 122. The polygonal forms 111 and 121 are relatively positioned so that the first opening 110 is nearer the anterior-end 1 than the posterior-end 2 and the second opening 120 is nearer the posterior-end 2 than the anterior-end 1. As such, the second opening 120 is predominantly below the midfoot and/or hindfoot during use, and the first opening 110 is predominantly below the forefoot during use. (The areas of the foot that form the hindfoot 3, midfoot 4, and forefoot 5 regions are depicted in FIG. 3.)

The openwork base 101 is configured so that the tread of the footwear is exposed and thus accessible to the terrain not only at the first and second openings 110, 120 but also in the region exterior to the polygonal forms. In some embodiments, the openwork base 101 is configured so that when a traction device 100 is disposed on footwear, at least 50% and up to 95% of the tread of the footwear is exposed (i.e., not covered by the openwork base). In some embodiments, the openwork base 101 is configured so that 65% to 85% or 65% to 75% or 75% to 85% of the tread of the footwear is exposed. In some embodiments, the openwork base 101 is configured so that 50% to 65% of the tread of the footwear is exposed.

A polygonal form (e.g., polygonal forms 111 and 121) comprises at least 3 sides that are angled relative to each other to define (enclose) an interior opening (e.g., opening 110 and 120). Each side meets and is coupled to an adjacent side at a vertex. The longitudinal axis of a side can be straight, but it can also be curved. A vertex is a region where two adjacent sides meet, and the interior facing surface (i.e., the surface of a polygonal form that defines the interior opening) at the vertex is angled or has a higher degree of curvature than the longitudinal axis of a side. In the embodiment

60

65

ments shown, the polygonal forms have filleted corners. In addition, where the stirrups (described below) are coupled to a vertex, the corners can also be filleted.

Traction bodies 130 are coupled to and protruding from a surface 103 (shown in FIG. 2B) of the openwork traction base 101 that is opposite the surface 104 (shown in FIG. 2A) that faces the underside of the footwear 200 during use. Traction bodies 130 are configured to engage the ground to increase traction and improve stability when traversing a steep, uneven, icy, and/or snow-covered terrain. The openwork traction base 101 has coupled thereto, at the surface 103, a first plurality of traction bodies 130a that are located nearer the anterior end 1 than the posterior-end 2 of the device 100 and a second plurality of traction bodies 130p that are located nearer the posterior-end 2 than the anterior-end 1. The first plurality of traction bodies 130a are predominantly disposed underneath the forefoot when the device 100 is in use, i.e., disposed on footwear where the openwork traction base 101 extends on the undersole of the footwear. The second plurality of traction bodies 130p are predominantly disposed underneath the hindfoot or midfoot and midfoot when the device 100 is in use.

First Polygonal Form

As mentioned above, the first polygonal form 111 can comprise at least four-sides 112, (such as 4, 5, 6, 7, 8, or more sides), and as such, at least four vertices 113. In the embodiment shown, the first polygonal form 111 has four sides 112, four vertices 113, and the sides are substantially the same length. In other embodiments, the first polygonal form 111 can be kite-shaped, such as the shape shown for the second polygonal form 120.

In embodiments, one, two, three, four, or more traction bodies 130a can be coupled to each of the four sides 112 of the first polygonal form 111. In embodiments with more than four sides 112, at least one side may not comprise any traction bodies 130a coupled thereto but at a minimum, four sides 112 will have traction bodies 130a coupled thereto. In the embodiment shown, the first polygonal form 111, as depicted in FIGS. 2A and 2B, has four sides 112 with 2 traction bodies 130 coupled to each side for a total of 8 traction bodies 130a.

In embodiments, the first polygonal form 111 is configured to have some elongatability which allows for a single size device 100 to accommodate multiple sizes of footwear. To facilitate, the first polygonal form 111 is oriented so that foremost vertex 113a and the hindmost vertex (the shared vertex) 113p of the first polygonal form are relatively positioned to each other such that the two vertices 113a and 113p intersect a single line (line AP) that generally extends between the forefoot and the hindfoot or that is substantially parallel to a longitudinal axis (line AP) of the traction device. Two vertices of the first polygonal form 111 not including the hindmost vertex (shared vertex) 113p of the first polygonal form are relatively positioned to each other such that the two vertices intersect a single line (line RL) that is substantially perpendicular to the single line (line AP) that generally extends between the forefoot and the hindfoot or a line that is substantially parallel to a longitudinal axis of the traction device.

Also facilitating the elongatability of the first polygonal form, the vertices of the first polygonal form are not particularly bulky as compared to the area of the openwork traction base supporting the traction bodies. Less bulk allows for the interior angle formed by the sides of the polygonal form meeting at a particular vertex to narrow or widen when tension is applied to the device along an anterior to posterior axis. Thus, in embodiments, no traction bodies

130a are located on the vertices 113a and 113p. And in a further embodiment, no traction bodies 130a are located on any of the vertices of the first polygonal form 111.

Filletted corners at the vertices can distribute the load and mitigate breakage at these regions. In embodiments, the first polygonal form 111 comprises filleted corners at one or more vertices 113 or at all vertices 113. Similarly, the corners where a stirrup 180 (discussed below) and a polygonal form meet, can be filleted corners as well.

10 Second Polygonal Form

As mentioned above, the second polygonal form 121 can comprise at least three sides 122, (such as 3, 4, 5, 6, 7, 8, or more sides), and as such, at least three vertices 123. In the embodiment shown, the second polygonal form 121 has four sides 122, four vertices 123, and the second polygonal form 120 is substantially kite-shaped. In other embodiments, the sides 122 of the second polygonal form 122 can be substantially the same length.

In embodiments, the first polygonal form 110 and the 20 second polygonal form 120 share one or two vertices. In the embodiments shown, the hindmost vertex 113p of the first polygonal form 110 is the foremost vertex 123a of the second polygonal form 120.

Similarly facilitating the elongatability of the second polygonal form 120, one or more vertex 123 (e.g., foremost or lateral vertices 123) of the second polygonal form 120 are not particularly bulky or wide as compared to the area of the openwork traction base 101 supporting the traction bodies or between traction bodies 130. Again, less bulk allows for the 30 interior angle formed by the sides of the polygonal form meeting at a particular vertex to narrow or widen when tension is applied to the device 100 along an anterior to posterior axis (e.g., along line AP). Thus, in embodiments, no traction bodies 130p are located on the vertices 123a. In 35 further embodiments, no traction bodies 130p are located on the lateral vertices 123. And in even further embodiments, no traction bodies 130p are located on any vertex 123 of the second polygonal form 120. In some embodiments, three vertices 123 consisting of the shared vertex 113p, the foremost vertex 113a, and the hindmost vertex 123p are 40 relatively positioned to each other such that the 3 vertices intersect a single line that is substantially parallel to a longitudinal axis (line AP) of the traction device 100.

In addition to the traction bodies 130a on the sides of the 45 first polygonal form 111, the openwork traction base 101 comprises 2, 3, 4, 5, 6, or more traction bodies 130p. These additional traction bodies 130p are disposed predominantly below the hindfoot or midfoot and hindfoot during use. Stated another way, the traction bodies 130p are nearer the 50 posterior-end 2 than the anterior-end 1.

In some embodiments, one or two or more of the at least 55 three traction bodies 130p are located on a side of the second polygonal form 121. For example, in the embodiment shown, a traction body 130p is located on two of the four sides 122 of the four-sided second polygonal form 121. The two sides 122 of the second polygonal form 121 are those that are nearer the posterior-end 2 than the anterior-end 1 than the other two sides 122 of the second polygonal form 121. In the embodiment shown, four traction bodies 130p 60 are coupled to an X-shaped form 135 and the four traction bodies 130p are substantially equidistant from the hindmost vertex 123p. As such, the traction bodies 130p are not coupled to the vertex 123.

Alternatively, other configurations of traction bodies 130p 65 can be used. FIGS. 2D(i) to 2D(iii) are schematics of embodiments of an openwork traction base 101 with alternative configurations for the traction bodies 130p. For

example, one of at least three traction bodies **130p** can be located on a vertex of the second polygonal form **121**, as illustrated in FIG. 2D(i). In FIG. 2D(i), three traction bodies **130p** are coupled to a triangular form **140**. The triangular form **140** shares a vertex **123**, specifically vertex **123p**, with the second polygonal form **121**, and a traction body **130p** is coupled to the triangular form **140** at each of its vertices **143**. As such, one traction body is coupled to the vertex **123p** of the second polygonal form **121**. In some embodiments, the triangular form **140** defines an opening and in others, the triangular form **140** is a triangular plate.

In other embodiments, no traction bodies **130p** are located on a side **122** or vertex **123** of the second polygonal form **121**. For examples, as illustrated in FIGS. 2D(ii) and (iii), four traction bodies are coupled to a circular form **150** and four-sided **160**, respectively, where a portion of the form **150/160** intersects with the vertex **123p** of second polygonal form **121**. No traction bodies **130b** are located at this area of intersection with vertex **123p**. The traction bodies **130p** of the four-sided form **160** are located on the vertices **164** of the form. The traction bodies **130p** of the circular form **150** are evenly spaced along the circular form **150**. In some embodiments, the four-sided form **160** or the circular form **150** defines an opening and in others, the four-sided form **160** or the circular form **150** is a four-sided plate or circular plate, respectively.

Traction Bodies

As noted above, a traction body **130** is a protrusion on the surface of the openwork traction base that engage with terrain to improve traction and stability. A close up view of a traction body **130** is depicted in FIG. 2B is provided in FIG. 2C.

With reference to FIG. 2C, each of the traction bodies **130** comprise a cleat **170** and a spike **175** coupled to the cleat. The cleat **170** is coupled to and protruding from a surface **103** of the openwork traction base **101** that is opposite the surface that faces the underside of the footwear during use. In embodiments, the openwork traction base **101** and the cleat **170** can be integrally formed. The cleat **170** is polymeric.

As for the shape of the cleat **170**, it is such to enhance traction. The cleat **170** can comprise a stepped or sloping surface or otherwise comprises surface protrusion or edges configured to engage terrain during use. As shown, the cleat can comprise a frusto-pyramidal-like shape. In some embodiments, such as the one illustrated herein, the cleat can comprise a cross-sectional shape, extending in a plane that is parallel to the longitudinal axis (line AP) that has concave sides **171** and chamfered corners **172**.

As for the height of a cleat **170**, as measured from the surface **103** of the openwork base **101** to the distal end **173** of the cleat, it can have a height between 3 mm to 10 mm. The height can be more or less depending on the thickness of the openwork base **101** and the height of the portion of the spike **175** that is exposed (i.e., the portion not embedded in the cleat). In some embodiments, the height of the polymeric cleat **170** can be 5 mm to 7 mm. In embodiments, the effective height (the distance from surface **104** to the tip of the spike) of a traction body **130** is between 8 mm and 16 mm. In embodiments, the effective height is between 10 mm to 13 mm, optionally wherein the polymeric cleat is between 5 mm and 7 mm.

Contributing to the effective height of the traction body and to further improve the ability of a traction body **130** to engage with the terrain, the free-edge portions of the openwork traction base **101** to which the traction body **130** is coupled is wider than the base of the traction body **130**, but

only by 0.5 mm to 2.5 mm on each side **171** and on two of the corners **172** of the traction body **130** or on all of the corners **172** and two of the sides **171**. Or in some embodiments, wider on each side **171** and two of the corners **172** by 8-15% of the widest portion of the traction body **130** or wider by 8-15% of the widest portion of the traction body **130** on all of the corners **172** and two of the sides **171**. In embodiments, the width of a portion of the openwork traction base to which the traction body is coupled is between 0.75 in-1.10 in.

The spike **175** comprises an anchoring base **176** (partially shown) and a traction tip **177**, wherein the anchoring base is wider than the traction tip **177** and the anchoring base **176** is held by the cleat **170**. The spike **175** can be composed of a metal and/or carbide. In some embodiments, the anchoring base is a metal, such as aluminum, and the traction tip **177** is carbide. In some embodiments, the traction tip **177** on the spike **175** has a concave or sunken surface such as that shown in FIG. 5. Specifically, the concave or sunken surface is such that the outer perimeter of the traction tip **177** is the initial surface of the spike **175** to touch the ground before a portion of the surface more interior to the perimeter (such as the centermost point) touches the ground. This structure has the advantages of increasing the initial pressure into the ground and forcing an edge to catch the surface immediately, thereby minimizing slippage of the spike (and nearly eliminating it altogether).

With reference to FIG. 2B, the surface **104** of the openwork traction base **101** facing the underside of the footwear during use can comprise a plurality of protrusions **190**, **195**. In the embodiment shown, the protrusions **190**, which can be small knobs or bumps, are positioned to in the vicinity—on the opposite side of—a traction body **130**. In the embodiment shown, the protrusions **195**, which are longer than the protrusions **190**, are positioned on the portion of the openwork traction base **101** between two traction bodies **130**. These protrusions can be integrally formed with the openwork traction base **101**. However, these protrusions **190/195** are do not contribute to the thickness values or relative thickness described herein. In embodiments, the height of the protrusions **190/195** from the surface is less than or equal to the thickness of the openwork traction base **101**. In embodiments, the height of the protrusions **190/195** can be within a range that allows for better surface area contact with the underside of the footwear while allowing for some engagement with the grooves in the sole of the shoe. In some embodiments, the protrusions **190/195** is between 0.02 inches to 0.06 inches or between 0.02 inches to 0.05 inches or between 0.02 inches to 0.04 inches. In some embodiments, the height of longer protrusions **195** can be no more than 0.05 inches or no more than 0.04 inches, and the height of shorter protrusions **190** can be no more than 0.04 inches or no more than 0.03 inches.

In terms of the thickness of the openwork traction base **101**, for the purpose of durability, a foremost vertex **113a** of the first polygonal form **111** has a thickness greater than the shared vertex **113p** or the remainder of the openwork traction base. The thickness of the openwork traction base can be between 0.1 in—0.2 in.

As for the width of the various sections of the openwork traction base **101**, it is widest about the traction bodies, as discussed above. Moreover, the portion of the openwork traction base **101** to which a traction body **130** is coupled can be wider than the portion of the openwork traction base **101** between two adjacent traction bodies **130** coupled to a single side **113**. In embodiments, the width of a portion of the openwork traction base between traction bodies is between

0.40 in—0.60 in. In some embodiments, within the first polygonal form 111, the portion of the openwork traction base 101 between two adjacent traction bodies 130 coupled to a single side 112 is wider than the portion of the openwork traction base between a vertex 113 and a traction body 130. The portion of the openwork traction base 101 interconnecting the at least three traction bodies 130_p in the hindfoot is wider than the portion of the openwork traction base 101 between a vertex 113 of the first polygonal form 110 and a traction body 130. In embodiments, the narrowest width of a section of the openwork traction base is 0.200 in—0.300 in, such as between a traction body 130_a and a vertex 113 or between the foremost vertex 123_p and the X-shaped form 135.

In embodiments, the openwork traction base 101 consists of a homogenous polymeric material, which can be a thermoplastic polyurethane. The polymeric material has a hardness of Shore 80 A to Shore 98 A. The openwork traction base 101 can be formed by injection molding of the polymeric material. As in the embodiment shown, the openwork traction base 101, the traction bodies 130, and the stirrups are integrally formed by injection molding of the polymeric material.

Stirrups

The footwear traction device comprises a footwear binding member 102 configured to secure the openwork traction base 101 to the underside of the footwear. The footwear binding member 102 is coupled to the openwork traction base 101 at 6 or more sites, such as 6, 7, or 8 sites. Stirrup 180 has a length sufficient to couple the elastic band 102 to the openwork traction base 101, whether directly or through an intervening component, such as a coupling ring. Stirrup 180 can be a chain, bar, or a narrow strip of material. As in the embodiment shown, stirrup 180 can be integrally formed with the openwork traction base 101. A stirrup 180 can be coupled to each vertex 113 of the first polygonal form 110 except for the hindmost vertex 113_p (or shared vertex) of the first polygonal form 111. A stirrup 180 can also be coupled to each of two vertices 123 of the second polygonal form 120, which are not the hindmost vertex 113_p of the first polygonal form (or shared vertex) or a hindmost vertex 123_p of the second polygonal form 120. In addition, in some embodiments, one, two, or more stirrups 180 can be coupled to the form to which the hindfoot traction bodies 130_p are coupled. A stirrup 180 can be coupled to the form at a location on the form that is nearer a traction body 130_p than a vertex.

As for the width and thickness of a stirrup 180, each stirrup 180 has a width that is substantially the same as at least one side of the second polygonal form. In embodiments, the width of a stirrup is between 0.15 in—0.30 in.

In embodiments, the thickness of a stirrup can be 0.1 to 0.2 in or 0.1 to 0.15 in. In some embodiments, the thickness of a stirrup 180 located on the lateral side of the device 100 can be less than the stirrups 180 located on an anterior-end 1 and/or a posterior end 2. For example, the thickness of a stirrup 180 located on the lateral side and coupled to the second polygonal form can be thinner than the remaining stirrups. In embodiments, the thickness of a stirrup 180 at an anterior-end 1 or a posterior end 2 can be 10% to 60% thicker than the lateral stirrups.

Footwear Binding Member

The footwear binding member 102 can be elastic band or a system of straps and fasteners that allow for secure fit of the device 100 to an item of footwear. The elastic band is made of a material that is more elastic and has a lower hardness than the openwork traction base.

Devices described and illustrated herein can be used on both paved surfaces and trail, including trails with steep rocky inclines.

The invention claimed is:

1. A footwear traction device comprising a polymeric traction base comprising a cleat, wherein the footwear traction device is configured such that the polymeric traction base engages with a ground surface during use, wherein the cleat comprises a cross-sectional shape that has four concave sides and chamfered corners, wherein the cleat comprises a frusto-pyramid-like shape and comprises a stepped surface.
2. The footwear traction device according to claim 1, wherein the cleat has a height between 3 mm to 10 mm.
3. A footwear traction device configured to be disposed about footwear comprising
  - an openwork traction base defining a first opening and a second opening,
  - the first opening defined by a first polygonal form having at least four sides with each side having 1 to 4 cleats coupled thereto and relatively positioned such that the first opening is predominantly below a forefoot during use;
  - the second opening defined by a second polygonal form having at least three sides and relatively positioned such that the second opening is predominantly below a midfoot and/or a hindfoot during use,
  - the openwork traction base having coupled thereto at least one cleat that is disposed predominantly below the hindfoot during use, and
  - wherein the openwork traction base and cleats comprise a polymeric material with a hardness of Shore 80A to Shore 98A.
4. The footwear traction device of claim 3, wherein a cleat is not located on any vertex of the first polygonal form.
5. The footwear traction device of claim 3, wherein on the first polygonal form, the portion of the openwork traction base between two adjacent cleats coupled to a single side is wider than the portion of the openwork traction base between a vertex and a cleat on the single side.
6. The footwear traction device of claim 3, wherein the portion of the openwork traction base to which the cleat is coupled is wider than the base of the cleat or wherein the width of a portion of the openwork traction base between traction bodies coupled to a single side is between 0.400 in-0.600 in and wherein the width of a portion of the openwork traction base to which the cleat is coupled is between 0.750 in-1.050 in.
7. The footwear traction device of claim 3, wherein the openwork traction base comprises a stirrup coupled to each vertex of the first polygonal form of the first polygonal form and to each of two vertices of the second polygonal form, wherein a stirrup is not coupled to the hindmost vertex of the first polygonal form or a hindmost vertex of the second polygonal form and wherein each stirrup is coupled to a footwear binding member.
8. The footwear traction device of claim 3, wherein each of the cleats is coupled to and protruding from a surface of the openwork traction base that is opposite the surface that faces the underside of the footwear during use.
9. The footwear traction device of claim 3, further comprises a plurality of spikes, wherein a spike is coupled to each of the cleats such that the spike engages with a terrain during use.
10. The footwear traction device of claim 9, wherein the spike comprises an anchoring base and a traction tip, wherein the anchoring base is wider than the traction tip and the anchoring base is held by the cleat to which it is coupled.

11. The footwear traction device of claim 10, wherein the traction tip comprises a sunken or concave surface and is configured engage with the terrain.

12. The footwear traction device of claim 9, wherein the openwork traction base and the cleats are integrally formed.

13. The footwear traction device of claim 9, wherein the cleat comprises a stepped or sloping surface.

14. The footwear device of claim 9, wherein the cleat comprises a cross-sectional shape that has four concave sides and chamfered corners.

15. The footwear device of claim 13, wherein the openwork traction base comprises sections supporting each of the cleats, wherein each of the sections of openwork traction base supporting each of the cleats is wider than the cleat which it supports.

16. The footwear traction device of claim 9, wherein the first polygonal form defining the first opening and the second polygonal form defining the second opening share one vertex.

17. The footwear traction device of claim 16, wherein 3 vertices including the shared vertex are relatively positioned

to each other such that the 3 vertices intersect a single line that is substantially parallel to a longitudinal axis of the traction device.

18. The footwear traction device of claim 9, wherein the openwork traction base comprises an X-shaped, four-sided, three-sided, or circular form positioned such that the X-shaped, four-sided, three-sided, or circular form is predominantly below the hindfoot during use wherein at least three cleats are coupled thereto and wherein the second opening is between the X-shaped, four-sided, three-sided, or circular form and the first opening.

19. The footwear traction device of claim 9, wherein the openwork traction base comprises a stirrup coupled to each vertex of the first polygonal form of the first polygonal form and to each of two vertices of the second polygonal form, wherein a stirrup is not coupled to the hindmost vertex of the first polygon form or a hindmost vertex of the second polygonal form and wherein each stirrup is coupled to a footwear binding member.

20. The footwear traction device of claim 9, wherein the polymeric material is a thermoplastic polyurethane.
